UNITED STATES PATENT OFFICE.

HUGH SNOWIE JONES, OF LANCASTER GATE, LONDON, ENGLAND.

STOCKING SUSPENDER.

Application filed November 16, 1922. Serial No. 601,395.

To all whom it may concern:

Be it known that I, HUGH SNOWIE JONES, a subject of the King of Great Britain and Ireland, residing at Lancaster Gate, London, England, have invented Stocking Suspenders, of which the following is a specification.

This invention relates to suspenders for ladies', gentlemen's or children's stockings, socks, and the like, and consists in providing means for locking the device against accidental disengagement while enabling it to be readily released when desired.

This end is attained by providing a lip or hook at or near the lower end of the usual keyhole-shaped member and a metallic ring half ring, loop or the like attached by a short length of elastic fabric or equivalent resilient means to the upper end of the keyhole-shaped member. The resilient attachment of the metallic ring is so dimensioned that when it is slightly stretched the said ring will catch in the lip or hook with its lower edge and at the same time will bear with its upper edge against the usual stud-like projection which slides in the keyhole-shaped slot, thereby preventing the said projection from sliding up into the wide part of the slot until the ring is released from the hook.

To enable the ring to be readily released at will it may be provided with a tab, which may be in the form of a knob or any little ornament by means of which it can easily be drawn downwards and then forwards.

In order that this invention and the manner in which it operates may be clearly understood it is illustrated in the accompanying drawings, wherein:

Fig. 1 is a perspective view of the suspender as a whole, in the open position;

Fig. 2 is a front elevation of the suspender when closed and locked;

Fig. 3 is a side elevation of the keyhole-shaped member provided with an upturned lip;

Figs. 4 and 5 show alternative forms of the locking ring;

Figs. 6 and 7 show, in front and side elevation respectively, a keyhole-shaped member having a modified form of hook;

Figs. 8 and 9 are similar views showing a third form of hook.

Fig. 10 is a perspective view of a keyhole-shaped member formed of bent wire.

In these drawings, *a* is the usual backing member, provided with a stud-like projection *b*, adapted to slide in a keyhole-shaped slot *c* in the member *d*, which has an upturned lip or hook *e* at or near its lower or narrow end. *f* is a ring of metal or other suitable material attached by a short strip *g* of elastic fabric to the upper end of the member *d*. The backing member *a* may if desired also be made of elastic fabric, and in that case the strip *g* and the backing member *a* may conveniently be made in one piece, passed through one or more slots in the upper end of the member *d* and suitably secured in position. Furthermore the same piece of elastic material may also if preferred serve for attaching the abovementioned parts to the suspension member, which is not shown in the drawing. *h* is a tab by which the ring *f* is pulled down for the purpose of locking or unlocking the device.

In Figs. 1 and 2, *f* is shown as a plain ring. It may however be provided with a slot *j* for the tab, as shown in Figs. 4 and 5; and, if desired, with a second slot *k* for the elastic strip, as shown in Fig. 5. Although described as a ring, it need not necessarily be circular but may be semicircular or of any other convenient shape.

The hook *e* may be formed by bending up the lower end of the member *d* as shown in Figs. 1, 3 and 10 or by cutting and bending outwards a tongue of metal from the body of the plate *d* near its lower end as shown in Figs. 6 and 7; or by making two cuts in the lower edge of the member *d* and suitably bending the strips of metal between them, as illustrated in Figs. 8 and 9.

In fastening this device, the upper edge of the stocking or sock is passed in the usual way between the backing *a* and the keyhole-shaped member *d*. The stud *b* covered by the edge of the stocking or sock, is then pushed through the wide upper end of the slot *c*, and slid down into the narrow part. Then in order to prevent the stud *b* from accidentally returning to the wide part of the slot *c* the ring *f* is pulled forwards and downwards by means of the tab *h*, thereby stretching the elastic fabric *g*, and the ring *f* is passed over the stud *b* and the lip *e* so that the tension in the elastic fabric *g* prevents them from being separated until the ring *f* is again drawn downwards.

What I claim is:—

1. A garment suspender of the kind described, comprising a backing member having a stud-like projection, a member having a key-hole shaped slot in which the projection is adapted to slide, a hook on the slotted member in the neighbourhood of the narrow end of the slot, and means engaging the hook and the projection to prevent relative movement thereof.
2. A garment suspender of the kind described, comprising a backing member having a stud-like projection, a member having a keyhole-shaped slot in which the projection is adapted to slide, a hook on the slotted member in the neighbourhood of the narrow end of the slot and a ring connected by a strip of elastic material to the upper end of the slotted member and adapted to

slip over the projection and also over the hook when the said strip is slightly stretched.

3. A garment-suspender of the kind described, comprising a flexible backing member having a stud-like projection, a member hinged to the backing member and having a keyhole-shaped slot in which the projection is adapted to slide, a hook on the slotted member in the neighbourhood of the narrow end of the slot, a ring connected by a strip of elastic material to the upper end of the slotted member and adapted to slip over the projection and also over the hook when the said strip is slightly stretched and means for releasing the ring from the hook.

Signed at London, England, this 7th day of November, 1922.

HUGH SNOWIE JONES.
